FRANK H. NICHOLSON, OF WEST HAVEN, CONNECTICUT.

RAILWAY-TRAFFIC-CONTROLLING APPARATUS.

1,317,639.

Specification of Letters Patent. Patented Sept. 30, 1919.

Application filed January 24, 1917. Serial No. 144,159.

To all whom it may concern:

Be it known that I, FRANK H. NICHOLSON, a citizen of the United States, residing at West Haven, in the county of New Haven and State of Connecticut, have invented certain new and useful Improvements in Railway - Traffic - Controlling Apparatus, of which the following is a specification.

My invention relates to railway traffic controlling apparatus, and particularly to apparatus of this character embodying railway signals which comprise electric lamps for giving indications to the drivers of cars or trains passing along the railway. More particularly my invention relates to means for varying the intensity of illumination of such lamps, to provide for a brilliant illumination or a comparatively weak illumination, depending upon the circumstances under which

20 the lamp is used.

For example, when the lamp is employed for giving indications both in daylight and darkness, the lamp must during daylight be illuminated at such intensity as to be clearly 25 visible during the brightest sunlight and under the worst conditions of relative position of the sun and the signal, namely, when the signal is directly between the observer and the sun; but it is undesirable that this 30 high intensity of illumination be maintained at night, because the light from the lamp would then be dazzling to the observer and the observation at frequent intervals of a succession of signals comprising such lamps 35 would have an undesirable physiological effect on the observer. It is therefore desirable that the lamps in such signals be illuminated at a high intensity for daylight indications and at a lower intensity for indications 40 during darkness.

One feature of my invention is the provision of means for causing the illumination of the lamps in such signals at one intensity for indications under certain conditions and 45 at a lower intensity for indications under other conditions.

I will describe one form of apparatus embodying my invention and will then point out the novel features thereof in claims.

50 The accompanying drawing is a view showing diagrammatically one form of apparatus embodying my invention.

Referring now to the drawing, the reference character R designates the track rails

of a railway adjacent which is located a signal S comprising, as here shown, three electric incandescent lamps L^G , L^Y and L^R , which lamps when illuminated are adapted to indicate respectively "Proceed," "Proceed with caution," and "Stop." I will assume that these lamps are employed for giving indications both in daylight and in darkness, and that therefore illumination of the lamps at one intensity for daylight purposes, and at a lower intensity for conditions of darkness, is desirable. The light from these lamps is usually concentrated into a beam of substantially parallel rays by means of a lens in front of each lamp, and the three beams are usually caused to differ in color by colored glasses located in such beams, but these lenses and colored glasses are omitted to simplify the drawing.

The three lamps L^G , L^Y and L^R are, as here shown, connected in multiple and are energized from a secondary s of a transformer T, the circuits for these lamps being apparent from the drawing. It is understood that the circuits for the individual lamps L^G , L^Y and L^R are controlled by other means depending on the conditions of traffic along the railway, but inasmuch as such means constitute no part of my invention they are omitted from the drawing for the purpose of simplicity. The primary p of transformer T is energized from the secondary 6^b of another transformer 6 the primary 6^a of which is connected with a suitable source of alternating current (not shown). The circuit for primary p of transformer T is from the lower terminal of secondary 6^b of transformer 6 through wires 7, 8 and 9, primary p , wires 10, 11 and 12, to substantially the middle point of the secondary winding 6^b . It will be obvious, therefore, that secondary p is energized at all times when alternating current is supplied to the primary of transformer 6.

It will be noted that the primary p and the secondary s of transformer T are located on different parts of a core 2 of magnetizable material, the portion of this core on which these windings are placed constituting a closed magnetic circuit, so that if no other means were provided the greater part of the magnetic flux created by the primary p would pass through the secondary s and so

generate a certain voltage in the secondary, depending chiefly on the voltage applied to the primary and the ratio between the number of turns in the primary and the secondary.

The transformer T is provided with means for varying the proportion of the magnetic flux created by the primary p which passes through the secondary s . As here shown, 10 this means comprises two legs 3 and 3^a integral with the core 2 and connected therewith at the opposite ends of the primary winding p . 4 is a member of magnetizable material movable toward and away from the 15 extremities of the legs 3 and 3^a. It will be apparent that when the member 4 is substantially in engagement with the legs 3 and 3^a, a certain portion of the magnetic flux created by the primary p will pass through 20 the member 4 and so will be shunted from the secondary s , thus reducing the proportion of the primary flux which passes through the secondary s and so reducing the voltage applied to the lamps of signal 25 S. The member 4 is biased by gravity or otherwise to a position wherein it rests on fixed stops 5, 5. When in such position the member is at such distance from the legs 3, 3^a that it is not attracted to these legs by 30 the magnetic flux created by the primary p , and that it diverts substantially none of the primary flux from the secondary when the transformer is under full load.

Suitable means are provided for moving 35 the member 4 into engagement with the legs 3 and 3^a. As here shown, this means comprises a winding 18 on the member 4, which winding is energized with alternating current of one instantaneous polarity or another with respect to the current in the 40 transformer primary p . In the arrangement here shown, one terminal 17 of winding 18 is connected with the middle point of the secondary 6^b of transformer 6 by means 45 of wires 11 and 12, and the other terminal 16 of winding 18 is connected with one end or the other of transformer secondary 6^b through the medium of wires 14 and 15 and a manually operable switch 13. This 50 switch 13 when swung to the left engages with a contact 13^a, which is connected with the lower terminal of the secondary 6^b, and when swung to the right engages with a contact 13^b, which in turn is connected with 55 the upper end of transformer secondary 6^b. It will be seen, therefore, that the instantaneous polarity of the current in winding 18 with respect to the current in primary p will depend on whether the switch 13 is 60 swung to the left or to the right.

The operation of the apparatus is as follows: When the switch 13 is in the middle position, as shown, and the movable member 4 is out of engagement with the transformer 65 core, as shown, the lamps of signal S will

be illuminated at their full intensity, as is desirable for daylight conditions. If now switch 13 is swung to the left, the winding 18 on member 4 will be energized with current of such instantaneous polarity with 70 respect to the current in primary p that the fluxes created by these two windings will co-operate to attract member 4 to the legs 3 and 3^a. Switch 13 may now be opened and the member 4 will remain in its attracted position due to the flux created by the primary winding p . A certain proportion of the primary flux is now diverted through member 4 and so is shunted from secondary s , thus reducing the voltage applied to the lamps of signal S to the desired degree for conditions of darkness. When it is desired to return the lamps S to the full intensity of illumination, the switch 13 is swung to the right, thus energizing winding 18 with current of the reverse instantaneous polarity with respect to the current in primary p , so that member 4 is then repelled from the core of transformer T and so returns to the position in which it is 80 shown in the drawing. The shunt path for the primary flux being then removed, the voltage applied to the lamps of signal S is 85 returned to its original value.

The control switch 13 is preferably located in a tower or other enclosure where it may readily be reached by the operator who is to control the intensity of the illumination of the lamps. It is understood that although only one signal S is shown 100 in the drawing, any number of signals may be controlled by the one control switch 13, each such signal being provided with a transformer T, each of which transformers is connected with the line wires 14, 11 and 8, 105 in the same manner as is the transformer T shown in the drawing.

Although I have herein shown and described only one form of railway traffic controlling apparatus embodying my invention, it is understood that various changes and modifications may be made therein within the scope of the appended claims without departing from the spirit and scope 110 of my invention.

Having thus described my invention, what I claim is:

1. In combination, a signal comprising an electric lamp, a source of alternating current, a transformer whose primary is energized from said source and whose secondary is connected with said lamp, a member of magnetizable material movable toward and away from the core of said transformer to shunt from the secondary a portion of 125 the magnetic flux created by the primary, a winding on said member, and means for energizing said winding with alternating current of one instantaneous polarity or another with respect to the current in the 130

primary whereby said member will be attracted to or repelled from the transformer core.

2. In combination, a signal comprising an electric lamp, a source of alternating current, a transformer whose primary is energized from said source and whose secondary is connected with said lamp, a member of magnetizable material movable toward and away from the core of said transformer to shunt from the secondary a portion of the magnetic flux created by the primary, said member being biased away from said core to such position that there is substantially no magnetic leakage therethrough when the transformer is under full load, and means for moving said member against its bias into substantial contact with said core and for repelling said member from said position, the member when in contact with the core being retained in such position by the primary flux flowing therein.

3. In combination, a signal comprising an electric lamp, a source of alternating current, a transformer whose primary is energized from said source and whose secondary is connected with said lamp, a member of magnetizable material movable toward and away from the core of said transformer to shunt from the secondary a portion of the magnetic flux created by the primary, said member being biased away from the core to such position that it is not attracted to the core by the primary flux in the core, a winding on said member, means for momentarily energizing said winding from said source with current of one instantaneous polarity with respect to the primary current whereby said member is attracted substantially into contact with the core, the member being retained in

such attracted position by the primary flux flowing therein, and means for momentarily energizing said winding from said source with current of the opposite instantaneous polarity with respect to the primary current whereby the member is then repelled from said core. 45

4. In combination, a signal comprising an electric lamp, a source of alternating current, a transformer whose primary is energized from said source and whose secondary is connected with said lamp, a member of magnetizable material movable toward and away from the core of said transformer to shunt from the secondary a portion of the magnetic flux created by the primary, said member being biased away from the core to a position in which it cannot be moved to the core by the primary flux alone in the core, a winding on said member, means for momentarily energizing said winding from a source of alternating current with current of one instantaneous polarity with respect to the primary current 65 whereby said member is moved by magnetic attraction substantially into contact with the core, the member being retained in such attracted position by the primary flux flowing therein, and means for momentarily 70 energizing said winding from a source of alternating current with current of the opposite instantaneous polarity with respect to the primary current whereby the member is then repelled from said core. 75

In testimony whereof I affix my signature in presence of two witnesses.

FRANK H. NICHOLSON.
